UNITED STATES PATENT OFFICE.

ZACHARY T. HALL, OF PHILADELPHIA, PENNSYLVANIA.

DESIGN FOR A REFLECTOR OR SHADE.

SPECIFICATION forming part of Design No. 20,724, dated May 19, 1891.

Application filed January 7, 1891. Serial No. 377,046. Term of patent 14 years.

To all whom it may concern:

Be it known that I, ZACHARY T. HALL, a citizen of the United States, residing in the city and county of Philadelphia, State of Pennsylvania, have invented and produced a new and original Design for a Reflector or Shade, of which the following is a specification, reference being had to the accompanying drawings, forming part thereof.

10 The leading feature of my design for a reflector or shade is the corrugated face of the same, the corrugations having their widest ends joined, forming a scalloped rim on top within the peripheral rim of the reflector or shade.

15 In the accompanying drawings, to which reference is made, Figure 1 represents a perspective view of a reflector or shade embodying my design. Fig. 2 represents a diametrical section thereof.

Similar letters of reference indicate corresponding parts in the two figures.

Referring to the drawings, A designates a reflector or shade having on the face thereof the radiating corrugations or scallops B, the same flaring or widening from center to circumference. The widest ends of the corrugations are joined, forming a scalloped rim on top within the peripheral rim of the reflector or shade.

30

I claim—

A design for a reflector, as shown and described.

ZACHARY T. HALL.
